JAMES BOOKER, OF SAN FRANCISCO, CALIFORNIA, ASSIGNOR OF ONE-HALF TO JOHN H. HENDERSON, OF SAN FRANCISCO, CALIFORNIA.

ROUND-TOP EXTENSION-TABLE.

1,079,099.

Specification of Letters Patent. Patented Nov. 18, 1913.

Application filed July 1, 1912. Serial No. 706,891.

To all whom it may concern:

Be it known that I, JAMES BOOKER, a citizen of the United States, residing at San Francisco, in the county of San Francisco and State of California, have invented new and useful Improvements in Round-Top Extension-Tables, of which the following is a specification.

The object of the present invention is to provide a round table of such construction that it can be extended or enlarged when greater capacity is needed, and can be folded or reduced in size when the smaller size is more convenient, in both cases retaining its circular form.

In the accompanying drawing, Figure 1 is a vertical section of my improved table extended; Fig. 2 is a horizontal section showing in bottom plan view the top of the table partly extended and partly folded or collapsed; Fig. 3 is a detail sectional view on the line 3—3 of Fig. 2, except that the folding leaf is in its intermediate position, not fully extended; Fig. 4 is a detail perspective view of an extension arm.

Referring to the drawing, 1 indicates a base, supported upon casters 2, and in which is fitted a standard 3. On the top of said standard, and supported thereby, is a hub 4 confined by bolts 5 between two metallic plates or disks 6, 7. A bolt 8 passes centrally through said disks, hub, standard, and base, and upon the lower end of said bolt is screwed a nut 9, whereby said bolt secures all of said parts together. From said hub extend radially, at equal angular intervals, six horizontal arms 11, upon which arms, and upon the hub 4, rests the table top proper 12. Said top is circular in form, and 40 has hinged thereto, each by two hinges 13 on the under side thereof, three extension leaves 14. Each leaf 14 is directly hinged to the under side of the table top 12, and is of a general arcuate shape, of uniform width 45 throughout its length, and of such a form that, when it is swung on its hinges so as to lie in the same plane as the table top 12, its inner arcuate edge, adjacent to said hinges 13, will fit closely against the edge of the table top, the outer edge will be in a circle having the same center as the table top 12, and its terminal edges will extend radially from said center. Wings 16, similar 50 in form to the leaves 14 except that they are only of one-half the length, are hinged, as

shown at 17, to each leaf at the radially extending ends of the latter, springs 18 being provided to move the wings upward into place. When each leaf, and the wings hinged thereto, are thus extended so as to 60 lie in the plane of the table top, they extend around through an angle of 120°, so that, when all of said leaves and wings are so placed, they form an annular extension of uniform width around the table top, and the 65 extended table top is still circular in form, but of greatly increased diameter.

Each arm 11 is formed in the upper side with a longitudinal channel extending substantially its whole length, and in which 70 can slide an extension arm 38, to the inner end of each extension arm is connected the inner end of a coiled spring 19, which can move in a groove 21 formed in the top of said extension arm, and the outer end of 75 which is connected to the under side of the table top proper 12. Three of these extension arms, when extended, lie beneath, and support, the central portion of the leaves 14, while the other three, alternating with the 80 former three, lie beneath and support the adjacent outer edges of the wings 16. In order to insure the wings and leaves making, when extended, closely fitting joints with the table top 12, so that the extended 85 table top will have a plane upper surface, their ends, when extended, engage spring plates 22 secured on the under sides of said leaves and wings.

In order to retain each extension arm in 90 its collapsed position against the action of its spring 19, said arm is formed on one side with a socket 24, which is adapted to be engaged by a latching lever 25 pivoted, as shown at 26, on the under side of the central 95 portion 12, and passing through a hole 27 in the side of the corresponding radially extending arm 11, the other arm of which lever is pressed in a direction to normally cause said latch 25 to enter said socket 24 by a 100 coiled spring 28 in a pocket 29 in the central section 12, and which other arm has a nose 31 arranged to be engaged by the wing or leaf, as the case may be, when being extended, to withdraw said latch 25 out of said 105 socket 24 to release the extension arm 18, so that it can be moved outward by the tension of its spring 19.

In order to support the extension leaves when in the folded or collapsed position, a 110

ring 34 surrounds the standards 3, and is supported thereon by screws 35 passing through slots 36. From said ring extend upwardly arms 37, which in one position of 5 said ring extend beneath said leaves when in their folded position. By revolving said ring through the length of said slot, said arms are moved to such a position that they no longer support said leaves, which can 10 then be extended.

I claim:—

1. In a round top extension table, the combination of a central standard, a hub thereon, arms radiating rigidly from said hub, a 15 round table top supported by said arm, extension leaves having inner and outer curved edges, each leaf being hinged to the under side of the table top in a line through the ends of the inner edge of said leaf, terminal 20 wings hinged to each extension at its ends, extension arms guided by said first-named arms for supporting alternately said leaves and wings, springs for projecting said extension arm, and latches for holding said 25 extension arms in their retracted position,

and arranged to be engaged and withdrawn by the inner edges of the leaves and wings when extended.

2. In a round top extension table, the combination of a central standard, a hub thereon, arms radiating rigidly from said hub, a round table top supported by said arm, extension leaves having inner and outer curved edges, each leaf being hinged to the under side of the table top in a line through the 35 ends of the inner edge of said leaf, terminal wings hinged to each extension at its ends, extension arms guided by said first-named arms for supporting alternately said leaves and wings, springs on the under sides of 40 said wings and leaves, adapted to be engaged by the upper sides of said extension arms when extended.

In testimony whereof I have hereunto set my hand in the presence of two subscribing 45 witnesses.

JAMES BOOKER.
